(57) **CLAIM**

The ornamental design for an extendable top for a recreational vehicle, as shown and described.

DESCRIPTION

FIG. 1 is a left-side view of the extendable top for a recreational vehicle, showing our new design.

FIG. 2 is a right-side view thereof;

FIG. 3 is a front view thereof;

FIG. 4 is a rear view thereof;

FIG. 5 is a top view thereof;

FIG. 6 is a front, right side perspective view thereof;

FIG. 7 is a rear, right side perspective view thereof;

FIG. 8 is a rear, left side perspective view thereof; and,

FIG. 9 is a front, right side perspective view thereof.

The broken lines in the drawings depict parts of the extendable top for a recreational vehicle that form no part of the claimed design. The broken lines in the figures also illustrate environmental subject matter and other features that form no portion of the claimed design.
